CLAIM

The ornamental design for a cart for recycling containers, as shown and described.

DESCRIPTION

FIG. 1 is a front and side perspective view of a cart for recycling containers showing my new design, the portion of the figure shown in broken lines representing recycling containers and forming no part of the claimed design;

FIG. 2 is a side elevational view thereof, the opposite side being a mirror image;

FIG. 3 is a rear elevational view thereof;

FIG. 4 is a front elevational view thereof;

FIG. 5 is a top plan view thereof; and,

FIG. 6 is a bottom plan view thereof.

FIG. 1

FIG. 4

FIG. 2

FIG. 3

FIG. 5

FIG. 6
